UNITED STATES PATENT OFFICE

GEORGE M. LONG, OF BRIGHTON, BOSTON, MASSACHUSETTS, ASSIGNOR TO WARREN
TELECHRON COMPANY, A CORPORATION OF MAINE

DESIGN FOR A CLOCK CASE

Application filed October 28, 1931. Serial No. 41,531. Term of patent 14 years.

To all whom it may concern:

Be it known that I, GEORGE M. LONG, a citizen of the United States, residing at 11 Durand St., Brighton, Boston, county of Suffolk, State of Massachusetts, have invented a new, original, and ornamental Design for a Clock Case, of which the following is a specification, reference being had to the accompanying drawings forming a part thereof.

Fig. 1 of the drawings is a front view of a clock case, and

Fig. 2 a side view thereof, showing my new design.

I claim:

The ornamental design for a clock case as shown.

GEORGE M. LONG.
